ERIC T. HESSLE AND WILLY LELGEMANN, OF LOCKPORT, ILLINOIS.

APPARATUS FOR THE CONVERSION OF HYDROCARBON OILS.

Application filed March 20, 1925. Serial No. 16,983.

Our invention relates to an apparatus for the conversion of hydrocarbon oils and is particularly useful in carrying out a process for this purpose as set forth in the co-pending application of Eric Th. Hessle "continuous process for the refining of mineral oils", Serial Number 678,924, filed December 6, 1923.

It is an object of our invention to provide a simple, compact and efficient apparatus for carrying out a process in which heavy hydrocarbon oils are converted into lighter hydrocarbon oils by subjecting the heavy oils to the action of a molten catalyzer.

Another object is to provide an apparatus which will be adapted to treat efficiently various grades of heavy hydrocarbon oils and residues from mineral oils.

Another object is to provide a fog producing device which will efficiently handle various grades of oils and which may be easily adjusted and kept in operative condition without removal during its operation.

Another object is to provide a fog producing device which will effect an impact between opposed streams of oil and gas with a consequent production of a homogeneous fog.

Another object is to provide an apparatus in which the production of a fog of the oil to be converted takes place in a closed zone which contains a molten catalyzer, and to so construct the vessel enclosing said zone as to cause the oil fog under pressure to be forced through said molten catalyzer.

Another object is to construct the vessel containing the molten catalyzer so that the speed of the fog of oil and gas through said catalyzer may be regulated in accordance with the nature of the oil to be converted.

Other objects will appear from the following description.

In the drawings—

Figure 1 is a side elevation partly in cross section of our reaction kettle;

Fig. 2 is a cross section taken on line 2—2 on Fig. 1;

Fig. 3 is a cross section taken on line 3—3, Fig. 1;

Fig. 4 is an enlarged cross section of our fog producing device shown in Fig. 1.

1 is the body of a reaction kettle which is formed with a partition 2 therein as shown. The partition 2 terminates a short distance

from the bottom of the body 1, and is formed at its lower end with a serrated and perforated portion 4. The partition 2 divides the interior of the kettle 1 into two compartments 5 and 6. It has been found satisfactory for the purposes in view to position the partition 2 so that compartment 5 has approximately one-eighth of the volume of the compartment 6. While we may construct the kettle 1 of any suitable material we have found that cast iron serves the purpose very satisfactorily. In the embodiment of our invention herein shown the body 1 and the partition 2 are cast integral.

On the wall of the body 1 and on one side of the partition 2 are a series of ribs 7 upon which are supported a series of removable perforated plates 8. The body 1 is provided at its top with a removable cover 9 which is held in place by bolts 10. Supported by the cover 9 is a tube 11 having a closed end 12 and a flanged open end 13, which is bolted to the cover 9 so as to make a fluid tight connection therewith. The tube 11 extends downwardly into the compartment 6 and through a portion of the plates 8, as shown. Within the tube 11 is placed a temperature responsive device 14 for indicating the temperature of the material within the compartment 6. The cover 9 is provided with an outlet conduit 15 leading from the compartment 6. A pressure gauge 16 and a temperature responsive device 17 are mounted on the plate 9 and are operatively positioned with respect to the compartment 5 so as to indicate the pressure and temperature therein.

18 is a fog producing device which is detachably mounted on the wall of the body 1 by means of a flange 19 having a body portion 20 projecting within the compartment 5. The body portion 20 has a passage 21 therein for gas to which is connected a gas supply fitting 22, which is screwed into the flange 19. An oil supply passage 23 in the body portion 20 connects with an oil supply fitting 24 which is also screwed into the flange 19. At the ends of the gas and oil supply passages 21 and 23 are mounted opposed oil and gas nozzles 25 and 26, respectively. These nozzles are threaded into the body portion 20 on opposite faces of a cut-away portion 27 and are so positioned that the discharge of oil impacts directly against the

discharge of gas. This impact produces an extremely fine dispersion resulting in a homogeneous fog of the oil and gas. The passage 21 has clean out holes 28 which are fitted with closing plugs, as shown. The fitting 24 has a passage 29 therein which connects with the passage 23 at the axis of said fitting, thus allowing the fitting to be turned in various circular positions of adjustment.

Mounted in the fitting 24 and passing through the passage 23 is a needle valve 30 having threads 31 thereon adapted to mate with threads 32 in the fitting 24. The inner end of the needle valve 30 is tapered as shown, and has a small rod-like end 33 which is adapted to pass through the nozzles 25 and 26, when the needle valve is brought to its forward position. The end 33 thus acts to clear the nozzles 25 and 26 of any material which would tend to clog the passages therein. This clearing out of the nozzles 25 and 26 may be accomplished while the apparatus is in action and without the removal of the fog producing device 18 from the kettle 1. This has a great advantage in the operation of our apparatus. The needle valve 30 is operated by a hand wheel 34. Oil is supplied under pressure by a pipe 35 to the fitting 24 and gas is supplied under pressure to the fitting 22 by a pipe 36.

Openings 37 are provided in the wall of compartment 5 which are fitted with look glasses 38, through which the operator may clearly see the fog producing operation and be advised of the adjustments necessary to effect perfect results.

The operation of our apparatus is as follows:—The kettle 1 is heated by a suitable source of external heat to the desired temperature which, under usual conditions, is between 350-450 degrees centigrade, which causes the catalyster therein to assume a molten state. We preferably use a catalyster composed of an alloy of tin and antimony. Oil is then supplied to the fog producing device 18 through supply pipe, 35 at a pressure of approximately 50-120 pounds per square inch and a temperature of approximately 200-400 degrees centigrade according to the nature of the oil employed. A hydrogenous gas is simultaneously supplied to the fog producing device 18 through the gas supply pipe 36 at an average pressure of 50 pounds per square inch. This pressure will vary in accordance with the nature of the oil employed, but will always be slightly below the pressure of the oil. This gives a more balanced impact between the jets of oil and gas issuing from the nozzles 25 and 26. The operator will view the production of the fog through the look glasses 38 and by adjustment of the needle valve 30 will be able to bring about a perfect dispersion and production of a homogeneous fog.

The temperature and pressure within the compartment 5 will be indicated by the pressure gauge 16 and the temperature responsive device 17. The pressure of the fog in the upper part of compartment 5 will press upon the molten catalyster and force the same downwardly in said compartment and consequently upwardly in the compartment 6 to the position shown by dotted lines in Fig. 1. The fog will pass through the molten catalyster by way of the serrations and perforations 4 at the end of the partition 2, and upwardly in compartment 6 through the perforated plates 8 until it escapes into the open space above the catalyster in compartment 6. Here it will change to vapor, being released from the internal pressure of the molten catalyster and will pass out through the outlet pipe 15 to suitable condensers or other apparatus. The perforated plates 8 serve to retard the flow of the fog through the catalyster and cause it to remain in contact therewith a greater length of time. This is particularly necessary when operating on heavy oils. One or more of the plates 8 may be removed to give more speed to the fog in accordance with the amount of time it is desired to keep the fog in contact with the catalyster. The passing of the fog of oil and gas through the catalyster presents the greatest possible surface of the oil being treated to the action of the catalyster, and consequently effects a very efficient conversion of the oil under the influence of the catalyster.

It will be seen that the oil is converted under the influence of the catalyster while in the liquid phase, which permits of a much larger quantity of oil being treated at one time than if the oil were treated in a gaseous phase. The temperatures and pressures employed are below those effecting a cracking reaction with the usual production of free carbon and fixed gas. The hydrogenous gas present in the reaction prevents oxidation and sulphuration of the catalyster which remains in the metal state for a long time.

Our apparatus will operate in a substantially continuous manner and be free from the usual shut downs caused by the collection of carbon deposits commonly experienced in the art.

Having described our apparatus, what we claim is:—

1. An apparatus for the conversion of heavy hydrocarbon oils into lighter hydrocarbon oils, a closed receptacle, an atomizing device mounted thereon having a discharge end projecting into said receptacle, said atomizing device having conduits therein for conducting oil and gas separately to said discharge end, opposed oil and gas nozzles mounted on said discharge end adapted to cause an impact between the discharging

streams of oil and gas, and a needle valve extending through said oil conduit and controlling the flow of oil therethrough.

2. An apparatus for the conversion of heavy hydrocarbon oils into lighter hydrocarbon oils, a closed receptacle, an atomizing device mounted thereon having a discharge end projecting into said receptacle, means for conducting oil and gas separately to said discharge end, opposed oil and gas nozzles mounted on said discharge end adapted to cause an impact between the discharging streams of oil and gas, and a needle valve for controlling the flow through one of said nozzles having a projection thereon adapted to pass through said oil and gas nozzles.

3. An apparatus for the conversion of heavy hydrocarbon oils into lighter hydrocarbon oils, a closed receptacle, an atomizing device mounted thereon having a discharge end projecting into said receptacle, said atomizing device having oil and gas conduits therein for separately conducting oil and gas to said discharge end, opposed oil and gas nozzles mounted on said discharge end adapted to cause an impact between the discharging streams of oil and gas, and a needle valve passing through said oil conduit adapted to control the flow of oil therethrough having a projection thereon adapted to pass through said oil and gas nozzles to clear them of obstructions.

4. In an apparatus for the conversion of oils, a fog producing device comprising a passaged body portion for conducting separate streams of gas and of oil, and nozzles at the end of said passages in spaced opposite relation to each other, whereby said gas and oil streams are caused to impact each other to form a fog.

5. In an apparatus for the purpose described, a reaction kettle, a partition dividing said kettle into two compartments communicating near the bottom of said kettle, said kettle being adapted to be partially filled with a stationary body of molten catalyst to a level above the lower edge of said partition and a device for producing an oil fog positioned in one of said compartments above the level of said catalyst, whereby said oil fog must pass through said catalyst in its course through said kettle.

6. In an apparatus for the catalytic conversion of oils, a reaction kettle, means defining two communicating passages therein, each of said passages lying outside of the other, a fog producing device having spaced opposed nozzles positioned within one of said passages, an oil conduit lying wholly outside of said kettle connected to one of the nozzles of said device and a gas conduit separate at all points from said oil conduit connected to the other of said nozzles, whereby a fog of oil and gas may be produced in said device and carried through a body of molten catalyst in said communicating passages.

7. In an apparatus for the catalytic conversion of oils, a reaction kettle, means defining two communicating passages therein, a device having spaced opposed nozzles positioned within one of said passages, an oil conduit lying wholly outside of said kettle connected to one of the nozzles of said device and a gas conduit separate at all points from said oil conduit connected to the other of said nozzles, whereby a fog of oil and gas may be produced in said device and brought in contact with a catalyst in said communicating passages.

8. In an apparatus for the catalytic conversion of oils, a reaction kettle, means defining two communicating passages therein, a device having spaced opposed nozzles positioned within one of said passages, an oil conduit connected to one of the nozzles of said device and a gas conduit separate at all points from said oil conduit connected to the other of said nozzles, whereby a fog of oil and gas may be produced in said device and carried through a body of fluid catalyst in said communicating passages.

In testimony whereof, we have signed our names to this specification this 19th day of March, 1925.

ERIC TH. HESSLE.
